UNITED STATES PATENT OFFICE

100,413

DESIGN FOR A GAITER ARCTIC

Kate Avery Clark, Wayne, Pa.

Application April 18, 1936, Serial No. 62,190

Term of patent 7 years

To all whom it may concern:

Be it known that I, Kate Avery Clark, residing at Wayne, in the county of Delaware and State of Pennsylvania, have invented a new, original, and ornamental Design for a Gaiter Arctic, of which the following is a specification, reference being had to the accompanying drawing, forming part thereof.

Fig. 1 is a perspective view of a gaiter arctic showing my new design with the zipper element partly in an open position; and

Fig. 2 is a side elevation thereof with the zipper element completely closed.

The design consists in the novel, artistic and distinguishing feature of so combining the sev-

eral elements as to give the design its unusual and pleasing appearance. The several elements consist of a vamp portion having the appearance of a dress shoe, a top portion having the appearance of a gaiter, and a bellows tongue so tapering upwardly from the arch of the sole to the top of the top as to present a marked wedge appearance. The appearance of a gaiter is further enhanced by a simulation of stitching down the front of the top.

I claim:

The ornamental design for a gaiter arctic, as shown and described.

KATE AVERY CLARK.
